GARMENT HANGER COVER

Edmund C. O'Gureck, Kearny, N. J.

Application May 26, 1941, Serial No. 395,147

2 Claims. (Cl. 223—98)

This invention relates to garment hangers and more particularly to new and useful improvements in a cover adapted for use with such hangers.

Heretofore, in the large cleaning establishments, it has been the custom to provide the garment hangers, which are usually made of wire, with a cover to protect the cleaned garment from being soiled by rust or dirt which may have accumulated upon the hanger. These covers are usually made from a thin paper, such as a tissue paper and in some cases from a cardboard material. However, while the tissue paper does protect the garment being supported from the effects of the wire hanger, it does not protect the garment from the unsightly creases and disfiguring marks caused by the wire hanger. The cardboard covers heretofore used have not obviated this objectionable feature since most of them are folded on scored lines and their sharp creases and corners leave imprints on the garments.

It is an object of this invention to provide an improved cover for garment hangers which is relatively simple and inexpensive in construction and efficient in use.

Another object of the invention is to provide a cover which may be applied to the ordinary garment hanger, whereby garments may be supported and carried to the best advantage due to the fact that they only come in contact with said cover.

Another object of this invention is to provide a cover which can be made of cardboard or other suitable material such as cellulose, folded into a shape to cover the hanger, made from a single blank, said blank being provided with end tabs and longitudinal slots so that when the tabs have been brought into locking engagement with the slots, hollow tubular shoulder-like portions are formed, rendering it admirably well for displaying garments, inasmuch as the cover has a shape conforming to the shape of the shoulders of a person, thereby providing a cover which has a maximum amount of rigidity and positively prevents sagging and undesirable creases.

These and other advantageous objects, which will later appear, are accomplished by the simple and practical construction and arrangement of parts hereinafter described and exhibited in the accompanying drawing, and in which:

Fig. 1 is a front elevational view of the improved cover,

Fig. 2 is a rear elevational view of the improved cover,

Fig. 3 is a top plan view thereof,

Fig. 4 is a view of the blank from which the cover is made,

Fig. 5 is a view of the blank folded along the dotted lines shown in Fig. 4,

Fig. 6 is transverse sectional view taken on line 6—6 of Fig. 1, looking in the direction of the arrows, showing the tabs passed through the slots of one of the sides of the cover, and

Fig. 7 is a similar view showing the tabs passed through registering slots in both the front and back sides of the cover.

Referring to the drawing, the cover 10 is formed from a blank 11, see Fig. 4, made from a single piece of suitable material, preferably cardboard or the like, rectangular in outline and provided with registering slots 12 and 13 near the longitudinal edges thereof. Each end of the blank is formed with marginal notches 14 and 15 to form tabs 16 and 17. A slot 18 is located centrally in the blank.

The blank is folded along the dotted line 19 to form a front and back side. The tabs 16 and 17 are then passed through the slots 12 and 13 with which they have locking engagement.

By passing the tabs 16 and 17 through both of the registering slots 12 and 13 (see Fig. 7) that is, through the registering slots in both the front and back sides of the cover, a more rigid cover 10 is provided, enabling heavier garments to be supported thereon. After the blank has been folded to form the cover it can simply and quickly be placed in position on the hanger by passing the hook of the hanger through the slot 18.

It is obvious that when the tabs 16 and 17 (see Fig. 5) are brought into locking engagement with the registering slots 12 and 13 (see Fig. 1) hollow tubular shoulder-like portions 20 are formed, and the cover is admirably well adapted for displaying garments, inasmuch as the cover has a shape to conform to the shape of the shoulders of a person, thereby providing a cover which has a maximum amount of rigidity and positively prevents sagging and undesirable creases.

The foregoing disclosure is to be regarded as descriptive and illustrative only, and not as restrictive or limitative of the invention, of which, obviously, embodiments may be constructed, including many modifications, without departing from the spirit and scope of the invention herein set forth and denoted in the appended claims.

Having thus described my invention, what I claim as new and desire to secure by Letters Patent, is:

1. A blank for a garment hanger cover formed from a sheet of suitable foldable material, com-

prising front and rear walls having an opening at the top edges thereof intermediate their lengths, whereby the cover may be disposed in covering relation to a hanger with a suspending element of the hanger projecting upwardly through said opening, each of said walls having a lower edge provided with slots, said walls having marginal notches adjacent the top edges thereof, said notches defining tabs adapted to have locking engagement with said slots to form shoulder-like portions on the cover.

10

2. A blank for a garment hanger cover formed from a sheet of suitable foldable material, comprising front and rear walls, each of said walls having a lower edge provided with slots, said walls having marginal notches adjacent the top edges thereof, said notches defining tabs adapted to have locking engagement with said slots to form shoulder-like portions on the cover.

EDMUND C. O'GURECK.
